UNITED STATES PATENT OFFICE.

ARTHUR A. HOPSON, OF TIPTONVILLE, TENNESSEE.

BACKBAND-HOOK.

1,375,911.

Specification of Letters Patent. Patented Apr. 26, 1921.

Application filed May 20, 1920. Serial No. 382,871.

To all whom it may concern:

Be it known that I, ARTHUR A. HOPSON, a citizen of the United States, residing at Tiptonville, in the county of Lake and State 5 of Tennessee, have invented certain new and useful Improvements in Backband-Hooks; and I do hereby declare the following to be a full, clear, and exact description of the invention, such as will enable others skilled in 10 the art to which it appertains to make and use the same.

The present invention relates to improvements in back band hooks, and has for an object to provide an improved device of this 15 character that will securely hold the back band to the traces while at the same time avoiding the cutting or wearing of the back band and prevent possible slipping of the same through the hook.

20 A further object of the invention is to provide a simple and inexpensive back band hook that will be capable of easy attachment to the traces and to the back band.

In the accompanying drawings forming 25 a part of this application, and in which similar reference symbols indicate corresponding parts in the several views:

Figure 1 is a partial view of a horse with the traces and back band applied and with 30 an improved hook constructed in accordance with the present invention shown as securing the back band to the traces.

Fig. 2 is a sectional view through the same.

35 Fig. 3 is a perspective view of the improved hook; and

Fig. 4 is a perspective view of a wooden or other piece used to coöperate with the hook.

40 Referring more particularly to the drawings, the traces are indicated at 1 and the back band at 2, there being chain links 3 inserted in the traces 1 to which the back band hook may be attached. It is obvious that 45 the traces 1 may be notched so as to receive the back band hook, or may be otherwise constructed, this forming no part of the invention.

50 The improved hook consists more particularly in a piece of sheet metal bent to provide a base plate 4 having a lower reduced end which is returned upon itself providing a bill 5 to engage with one of the links 3 of the traces. The bill 5 is preferably provided with a keeper 6 formed of a strip of 55 resilient sheet metal riveted or otherwise se-

cured to the base plate 4 as represented at 7, and preferably having its end engaging with a crimped portion 8 of the bill 5. Of course the keeper 6 could be made of the same piece of metal as the base plate 4, if desired. The sheet metal is looped outwardly from the plate 4 to provide a casing 9 in which the back band 2 is pushed.

A stick or bar 10 of wood or other material, is driven into the casing 9 after the back band 2 has been inserted therein in the manner indicated in Fig. 2. The bar 10 holds the back band tightly in the casing 9, forming a bight therein and effectually preventing the slipping thereof.

The casing 9 is of resilient metal and will yield and expand when the piece 10 is driven thereinto so that the resilient metal constantly tends to bind about the back band 2 and to squeeze it about the piece 10. This 75 forms a very effective way of securing the back band and preventing its slipping.

Arms 11 extend from the base plate at each end beyond the casing 9 and receive 80 the overturned edges 12 of the upper end of the plate 4. The ends of the arms may be soldered or otherwise secured in the edges 12 and the turning over of the edges forms a reinforce for the casing and base plate. 85

In use the back band 2 is looped and pushed through the base plate 4 into the casing 9, after which the bar 10 is driven through the casing and through the looped back band, thus holding the same tightly 90 in place. The bill 5 is engaged with one of the links 3 of the traces 1 and the device is then in a position of use, as indicated in Fig. 1. The back band 2 may be tightened by removing the bar 10 and drawing on the 95 lower end thereof, after which the piece is re-inserted.

The device forms a very effective hook for the back band and may be made up cheaply.

It is obvious that those skilled in the art 100 may vary the details of construction and arrangements of parts without departing from the spirit of my invention, and therefore I do not wish to be limited to such features except as may be required by the claims. 105

I claim:

1. An improved back band hook composed of sheet metal and comprising a base plate having a reduced hook at one end, a keeper for the hook, a casing bent out of the plane 110 of said base plate and adapted to receive the back band in a looped condition, and a

wedge bar adapted to be driven endwise through the casing and through the looped back band and constructed and arranged to bind the latter against the walls of the casing, substantially as described.

2. An improved back band hook including a base plate having a hook at one end with a crimped portion, a spring keeper attached to said base plate and engaging the crimped portion of the hook, a casing bent

outwardly from the plane of the base plate and adapted to receive the looped back band, arms at the ends of the casing, the edge of said base plate being doubled over and engaging the free ends of said arms, and a bar 15 having beveled edges adapted to be driven endwise through the casing and through the looped back band therein, substantially as described.

ARTHUR A. HOPSON.
